UNITED STATES PATENT OFFICE.

JULIUS FERDINAND BECKER, OF ELBING, GERMANY.

DEVICE FOR LOWERING LIFE-BOATS.

SPECIFICATION forming part of Letters Patent No. 758,043, dated April 26, 1904.

Application filed January 18, 1904. Serial No. 189,570. (No model.)

To all whom it may concern:

Be it known that I, JULIUS FERDINAND BECKER, a citizen of the free and Hanseatic town of Hamburg, and a resident of 30 Fisch-erstrasse, Elbing, in the Province of Prussia, German Empire, have invented certain new and useful Improvements in Devices for Lowering Life-Boats, of which the following is an exact specification.

10 My invention relates to a new and improved hoisting device for life-boats; and it has for its purpose to provide a device by means of which the boats can be easily and quickly lowered, requiring only few people and allowing lowering on both sides of the hull even when the hull is in an inclined position.

15 In order to make my invention more clear, I refer to the accompanying drawings, in which—

20 Figure 1 is a front view of the whole device. Fig. 2 is a diagrammatic view showing the position of several parts. Fig. 3 is a side view of part of the device. Fig. 4 shows the lowering of a boat when the ship-hull is inclined.

25 Figs. 5, 6, and 7 are views of detail parts of the device.

30 In the drawings, *a* is the life-boat, which, as shown in Figs. 1 and 3, is suspended by davits *b*, which project only slightly.

35 *c* is a pulley-block suspended by the davits *b*.

40 *d*, Figs. 3 to 7, is a sister-block provided with two pulleys, situated one behind the other. The sister-block *d* is situated in the fork-shaped end of a boom *e*, which can be turned around its end *f*, Figs. 1, 2, and 3, in the horizontal as well as in the vertical direction. The sister-block *d* is connected by means of a hook *g*, Figs. 5 to 7, with a pulley-block *c'*. The booms *e* are not quite vertical, but are inclined somewhat (about eight degrees) outward.

45 If the rope *h*, passing around the pulleys of the blocks *c c'*, is loosened, the boat, which is suspended to the pulley-blocks *c'*, can be lowered, and in consequence of the arrangement of the booms *e* the boat will, even if the ship-hull is in an inclined position, swing outward during the lowering. If the booms are in the horizontal position, the boat is situated at the greatest distance from the

ship-hull. Shortly before it arrives in this 50 position the hook *g*, which is fixed to the boom *e* and which serves for holding the pulley-block *c'* in position, is automatically detached from the pulley-block *c'* by means of a rope *i*, which, as shown in the drawings, is fixed at 55 one end to this hook and at the other end to the boom *e*. The life-boat can then be lowered, as may be seen from Fig. 7. It will be understood that the hook *g* may also be released by hand.

60 By the arrangement of the booms *e* the boat is lowered at a greater distance from the ship-hull than is the case with the ordinary devices, and it is not necessary for the boat to be shifted outward, as this movement is effected automatically by the swinging out of the booms. Even when the ship-hull is situated in an inclined position, as shown in Fig. 4, the boat can be freely lowered from the higher side of the deck. By this new arrangement even boats 70 suspended more toward the middle of the deck, as shown in the right-hand side of Fig. 4, can be easily lowered. The booms may also be used as so-called "coaling-booms" for loading coal, as well as for loading or unloading 75 smaller loads.

For fixing the boat in the normal position to the deck a ladder *m* may be used, enabling the boat to be easily entered.

80 As will be seen from Figs. 1 and 3, the boat is suspended to the pulley-blocks *c'* by means of hooks *n*, Figs. 5 and 6, fixed to ropes *k*, which are situated on both sides of the floor-heads. The ropes *k* are fixed, by means of suitable devices *o*, at different places to the 85 ship-hull. The boat, which on account of the small projection of the davits must be suspended at its extreme ends, is thus considerably strengthened.

Having thus fully described the nature of 90 my invention, what I desire to secure by Letters Patent of the United States, is—

1. In a device for lowering life-boats, the combination of davits *b*, a pulley-block *c* suspended by each davit *b*, pulley-blocks *c'*, a 95 boat suspended by the pulley-blocks *c'*, ropes *h* passing round the pulleys of each pair of blocks *c* and *c'*, booms *e* turnable around their

ends *f* and inclined somewhat outward in the normal position of the boat, a sister-block *d* fixed to each boom, said sister-block being provided with pulleys for guiding the ropes *h* and 5 hooks *g* for suspending the blocks *c'* to the sister-blocks *d*, substantially as described and for the purpose set forth.

2. In a device for lowering life-boats, the combination of davits *b*, a pulley-block *c* suspended by each davit *b*, pulley-blocks *c'*, a boat suspended by the pulley-blocks *c'*, ropes *h* passing round the pulleys of each pair of blocks *c* and *c'*, booms *e* turnable around their ends *f* and inclined somewhat outward in the normal 15 position of the boat, a sister-block *d* fixed to each boom, said sister-block being provided with pulleys for guiding the ropes *h*, hooks *g* for suspending the blocks *c'* to the sister-blocks *d*, and means for automatically releasing 20 said hooks during the swinging downward of the booms *e*, substantially as described for the purpose set forth.

3. In a device for lowering life-boats, the combination of davits *b*, a pulley-block *c* suspended by each davit *b*, pulley-blocks *c'*, a boat suspended by the pulley-blocks *c'*, ropes *k* situated on both sides of the floor-head of the boat, hooks *n* for suspending the boat to the pulley-blocks *c*, said hooks being fixed to 25 the ropes *k*, ropes *h* passing around the pulleys of each pair of blocks *c* and *c'*, booms *e* turnable around their ends *f* and inclined somewhat outward in the normal position of the boat, a sister-block *d* fixed to each boom, 30 said sister-block being provided with pulleys for guiding the ropes *h* and hooks *g* for suspending the blocks *c'* to the sister-blocks *d*, 35 substantially as described and for the purpose set forth.

substantially as described and for the purpose set forth.

4. In a device for lowering life-boats, the combination of davits *b*, a pulley-block *c* suspended by each davit *b*, pulley-blocks *c'*, ropes *h* passing round the pulleys of each pair of blocks *c* and *c'*, booms *e* turnable around the ends *f* and inclined somewhat outward in the normal 40 position of the boat, a sister-block *d* fixed to each boom, said sister-block being provided with pulleys for guiding the ropes *h*, hooks *g* for suspending the blocks *c'* to the sister-blocks *d*, and a ladder *m* for fixing the boat in the normal position, substantially as described and for the purpose set forth.

5. In a device for lowering life-boats, the combination of davits *b*, a pulley-block *c* suspended by each davit *b*, pulley-block *c'*, a boat suspended by the pulley-blocks *c'*, ropes *h* passing around the pulleys of each pair of blocks *c* and *c'*, booms *e* turnable around their ends *f* and inclined somewhat outward in the normal 45 position of the boat, a sister-block *d* fixed to each boom, said sister-block being provided with pulleys for guiding the ropes *h*, hooks *g* for suspending the blocks *c'* to the sister-blocks *d*, and a ladder *m* for fixing the boat in the normal position, substantially as described and for the purpose set forth.

In testimony whereof I have signed my name to this specification in the presence of two subscribing witnesses.

JULIUS FERDINAND BECKER.
